UNITED STATES PATENT OFFICE.

MASCHIL D. CONVERSE, OF NEW YORK, N. Y.

CORK-EXTRACTOR.

SPECIFICATION forming part of Letters Patent No. 624,457, dated May 9, 1899.

Application filed July 12, 1898. Serial No. 685,724. (No model.)

To all whom it may concern:

Be it known that I, MASCHIL D. CONVERSE, a citizen of the United States, residing in the city, county, and State of New York, have invented certain new and useful Improvements in Cork-Extractors, of which the following is a specification.

Cork-extractors have been made with prongs which in use are inserted next the inner sides of the neck of the bottle on opposite sides of the cork by pressure to embrace the latter. It is to this class of cork-extractors that my present invention relates. In this type of cork-extractors heretofore various devices have been employed to adapt the prongs to operate on corks of different diameters, involving more or less complication, consequent costliness of manufacture, and liability to derangement or breakage, and in all the flat external plane surfaces of the blades or prongs have been arranged at right angles to the longitudinal axis or plane of the handle, so that it is inconvenient to adjust the prongs astride the cork.

The objects of my present invention are to overcome these several disadvantages, to cheapen the cost of manufacture, and to provide a cork-extractor of the type described that will be durable and that may be expeditiously used, all of which I accomplish by means of the devices, combinations, and arrangement of parts and the forms of their construction hereinafter fully described and claimed, wherein it will be found that my in-

vention consists chiefly in first arranging the flat plane sides of the tapering prongs in planes parallel to the axis of the handle; second, in improved means of securing the prongs to the handle and in certain other particulars.

In the drawings, Figure 1 is a vertical longitudinal sectional view on line $x-x$ of Fig. 2, showing construction and form of my invention in part. Fig. 2 is a vertical cross-section of Fig. 1 on line $z-z$, with prongs shown in full, further showing construction and form of my invention. Fig. 3 is a full bottom-side view of the handle, further showing the form of construction of this part of my invention. Fig. 4 is a vertical cross-section (similar to Fig. 2) on line $z-z$ of Fig. 1, showing method of assembling and the manner of operation of parts of my invention relating to the man-

ufacture. Figs. 5 and 6 (partly sectional) show the application of my improved cork-extractor and the operation of features thereof. Figs. 7 and 8 (partly sectional) further show the operation and adaptation of features of my invention; and Fig. 9 illustrates a modification of a feature of my invention relating to manufacture, all of which will hereinafter be more particularly referred to in detail.

Like letters indicate corresponding parts throughout the several figures.

A is a handle, preferably of wood and which may be of any desired external conformation, having a circular recess B milled into its under side midway between its ends and at right angles to its longitudinal axis to form a socket for the reception of a tubular sleeve-shank C and provided with two flattened sides $a-a'$ (seen clearly in Fig. 3) on the lateral sides of the core D, forming seats for the butt-ends of the prongs $b-b'$, respectively, said prongs having the extreme ends of their butts turned sharply inward at $c-c'$, as shown in Figs. 2 and 4, to be forced into the wood of the handle when manufactured to insure their stability. Referring to Fig. 4, the operation of this part of my invention is as follows: The respective parts having been constructed as shown, are assembled by dropping the butts of the prongs $b-b'$ into the recess B, respectively at the flattened sides $a-a'$ of the core D, as shown. The tubular sleeve-shank C is now placed over outside of the prongs with its beaded end d toward their points, and its upper squared-off end e is now entered in the circular recess B, which it fits snugly, and firmly driven to the bottom thereof. This operation forces the turned edges $c-c'$ firmly into the wood of the core D of the handle A, whereby the respective parts are securely assembled, as may be seen in Fig. 2. A modified construction of this feature of my invention I have shown in Fig. 9, where instead of leaving a core in the handle A a hole large enough to receive the tubular sleeve-shank C very snugly is bored in the side of the handle, right angularly to the longitudinal axis or plane thereof. The turned edges c^2-c^3 on the prongs $b-b'$ are bent outward, and a separate core D' of wood or other suitable substance of the same form and dimensions as the core D is driven in through the open end of the sleeve-

shank C to the bottom of the hole, which forces the said turned edges c^2 c^3 outwardly under the inner edge of the sleeve-shank into the wood of the handle, as seen.

5 It will be seen that I arrange the flattened plane sides of the prongs b b' in planes parallel to the longitudinal axis of the handle A. It will also be seen that for a part of their length I curve the protruding ends outward 10 away from each other, (shown distinctly at f f' in Figs. 2, 4, and 9,) and it will further be seen by Figs. 2, 4, 5, 6, 7, 8, and 9 that I bevel the working ends of the prongs b b' from the inside to form sharp chisel edges g g' , 15 respectively, on the outer edges and flush with the other sides thereof. The purposes of these several devices will respectively appear in the following description of operation.

The handle of my improved cork-extractor 20 is grasped in the hand in the manner shown by Fig. 5. As I have arranged the prongs b b' in planes parallel to the longitudinal axis of the handle A the flat external side of prong b is consequently within ready reach of the 25 ball of the index-finger and the flat external side of the prong b' is likewise presented to the ball of the thumb, whereby the said prongs may be manipulated with great facility, which in this type of cork-extractors has heretofore 30 been unprovided for. If the cork to be withdrawn overhangs the mouth of the bottle, the outwardly-beveled sharp chisel edges g g' , being placed as shown in Fig. 5, will by reason of the sole of the same as they are forced 35 down cut their way promptly outwardly to opposite sides of the cork, as shown by Fig. 6, and go down between the surfaces of the cork and bottle-neck, whereas if the prongs were not beveled from the inside outwardly 40 they would pierce the body of the cork and fail to perform their functions, and, furthermore, if the extreme chisel-shaped cutting edges were made to project beyond the vertical plane surface of the adjacent outer flat 45 sides of the prongs they would by bearing against the interior of the bottle-neck press the prongs away from the same and unduly embed the prongs into the exterior lateral surface of the cork, with consequent liability 50 to force the cork into the bottle.

Figs. 7 and 8 show how by reason of the described arrangement of the prongs in the handle the points g g' are made conveniently accessible to and may by the thumb and finger be pressed together and promptly adjusted to strike varying sizes of corks.

The prongs are most readily inserted to place by rocking the instrument from side to side in the direction alternately of the prongs 60 b b' , respectively, pressing down firmly, which operation is possible by reason of the employment of thin elastic steel for the prongs and mounting the same in a tubular sleeve-shank. To withdraw the cork, rotate and pull on the 65 handle gently.

The prongs b b' I make from tough but very elastic thin steel, as stated, and by curving

their working ends from a point midway their length considerably outward from each other and stopping off the core D, so as to leave the 70 interior of the projecting end of the sleeve-shank open or hollow to provide greater length of elasticity for the prongs, they readily follow the neck of the bottle, even though the line may be wavy, and are thereby further 75 rendered equally well adapted for corks of large or small diameter.

Concerning the leading feature of my invention—viz., the arrangement of the external flat sides of two cork-embracing prongs 80 each in planes parallel to the longitudinal plane of the handle, so that said flat sides shall be conveniently accessible to the thumb and finger of the operator, as shown—I do not limit myself to the precise means described 85 for securing these prongs in such positions, as other means might be employed without departing from the spirit of this part of my invention.

Having described my invention, what I 90 claim as new, and desire to secure by Letters Patent, is—

1. In a cork-extractor, in combination, a handle, a circular recess right angularly therein, a core, flattened surfaces on opposite sides 95 of said core with the planes of said flattened surfaces arranged parallel to the longitudinal plane of said handle, a tubular sleeve-shank and two cork-embracing prongs, fixed within said sleeve-shank on the said flattened surfaces of said cork, respectively provided with turned edges at the butt-ends thereof in engagement with said handle, substantially as and for the purposes shown and described.

2. In a cork-extractor, in combination, a 100 handle, a hole right angularly therein, a tubular sleeve-shank entered in said hole, an insertible core securely fixed in said handle and bottom of said sleeve-shank, two fixed cork-embracing prongs, respectively provided with 105 turned edges at the butt-ends thereof in engagement with said handle, said prongs arranged so that the flattened plane sides thereof are parallel to the longitudinal plane of the handle, substantially as and for the purposes 110 shown and described.

3. In a cork-extractor, a handle and two flat cork-embracing prongs secured thereto with their flattened plane sides permanently arranged parallel to the longitudinal plane of 115 said handle, substantially as and for the purposes set forth.

4. In a cork-extractor, a handle having a socket therein, and a tubular sleeve-shank of substantially uniform interior diameter 125 throughout its depth extending from and secured within said socket, in combination with two thin, flexible cork-embracing prongs rigidly fixed in said handle at the base of and within said sleeve-shank on opposite sides 130 thereof, substantially as and for the purposes set forth.

5. In a cork-extractor of the type described, a suitable handle, a socket within the same,

a tubular sleeve-shank secured within and projecting from said socket, the interior of the projecting portion of which is hollow for a distance considerably above and from the 5 outer end, and two thin, flexible cork-embracing prongs secured within and adjacent to opposite sides of said sleeve-shank above said

hollow portion to provide greater length of elasticity for said prongs, as set forth.

MASCHIL, D. CONVERSE.

Witnesses:

PAUL GORHAM,
DWIGHT W. DE MOTTE.

It is hereby certified that in Letters Patent No. 624,457, granted May 9, 1899, upon the application of Maschil D. Converse, of New York, N. Y., for an improvement in "Cork-Extractors," an error appears in the printed specification requiring correction, as follows: In line 101, page 2, the word "cork" should read *core*; and that the said Letters Patent should be read with this correction therein that the same may conform to the record of the case in the Patent Office.

Signed, countersigned, and sealed this 8th day of August, A. D., 1899.
